Primary Examiner—James M. Gandy*Assistant Examiner*—Robert M. Spear*Attorney, Agent, or Firm*—John Edward Roethel**[57] CLAIM**

The ornamental design for a tool holder, as shown and described.

DESCRIPTION

FIG. 1 is an isometric view of the tool holder showing my new design, with an air line attachment shown in broken lines. The broken line showing of the air line attachment is for illustrative purposes only and forms no part of the claimed design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left elevational view thereof; and,

FIG. 7 is a right elevational view thereof.
